CLAIM

The ornamental design for a bottle carrier, as shown and described.

DESCRIPTION

FIG. 1 is a top perspective view of our new and ornamental design for a bottle carrier;

FIG. 2 is a front elevation view thereof, wherein the rear elevation view is identical;

FIG. 3 is a left side elevation view thereof, wherein the right side elevation view is identical;

FIG. 4 is a top plan view thereof;

FIG. 5 is a bottom plan view thereof;

FIG. 6 is a bottom perspective view thereof;

FIG. 7 is a top perspective view of the bottle carrier with a handle of the bottle carrier shown in an alternate position;

FIG. 8 is a front elevation view thereof with the handle in the alternate position, wherein the rear elevation view is identical; and,

FIG. 9 is a left side elevation view thereof with the handle in the alternate position, wherein the right side elevation view is identical.

The broken lines midway through the handle represent the bounds of the claimed design while all other broken lines beyond the bounds of the claimed design are directed to environmental subject matter; the broken lines form no part of the claimed design.
